United States Patent Office.

GEORGE B. KIRK, OF NEWARK, NEW JERSEY.

Letters Patent No. 73,813, dated January 28, 1868.

IMPROVEMENT IN PIPE AND BOLT-CUTTER.

The Schedule referred to in these Letters Patent and making part of the same.

TO ALL WHOM IT MAY CONCERN:

Be it known that I, GEORGE B. KIRK, of Newark, in the county of Essex, and State of New Jersey, have invented a new and improved Pipe-Cutter; and I do hereby declare that the following is a full, clear, and exact description thereof, which will enable those skilled in the art to make and use the same, reference being had to the accompanying drawings, forming part of this specification, in which—

Figure 1 is a side elevation of my improved cutter with a removed section.

Figure 2 is a side view, the reverse of that shown at fig. 1.

Figure 3 is a detail view of the cutter-stock.

Similar letters of reference indicate corresponding parts.

This invention relates to the cutting of pipes or rods, and consists of a stock containing a cutting-tool, which is made to traverse around the pipe, and thereby cut a section of the same at right angles to the axis.

The pipe-cutter heretofore in use was that of J. E. Stanwood, patented April 29, 1859, in which a cutting-wheel was made to revolve with its edge in contact with the pipe or rod. The use of this invention is attended with certain disadvantages, one of which being the compression of the pipe at the section cut, whereby it has fallen into disfavor, and in the manufacture of tubular boilers, where such an implement would, if unobjectionable, be generally employed, its use is discarded altogether.

My improvements obviate the objectionable features of the above-cited invention, and furnish a portable tube or pipe-cutter which is practically successful, without compressing the pipe or tube, as aforesaid.

In the drawings, A is the stock, having an angular recess, a, as shown. The claw B is provided with a screw-shank, b, which passes through the guides C C, forming part of the stock A. A screw-thimble, D, having a hollow thread which fits the screw-shank b, enables the claw B to be adjusted to different-sized pipes or rods. A rectangular opening, E, in the stock, is partially filled by the tool-holder G, the edges of which are V-shaped, to fit within the corresponding V-shaped sides of the opening E. A removable plate, h, forms part of the opening, and its removal permits the entrance of the holder G when the implement is being put together. This tool-holder is further provided with a slot for holding the cutting-tool d, as shown, and a set-screw, e, for clamping the latter firmly. The cutting-tool projects from the holder G into the angular recess, as shown, whereby its point will come in contact with the pipe when the latter is in the grasp of the stock A and claw B. The handle I serves to turn the implement around upon the pipe, and while so turning, the tool d takes out a thin cutting, which escapes through the slot n. This slot is of especial importance, for without it, or some equivalent outlet, the cutting would curl up and get between the grasp of the stock and the pipe or rod, and thus hinder the action of the implement. The shank l of the handle I works within a hollow screw formed in the stock, for the purpose of withdrawing the tool-holder G and its cutter, or actuating the same against the pipe or rod; and to accomplish this end it is formed with a flange, i, as shown at fig. 3. A pin, g, is secured in the holder G, below this flange, whereby the former is made to follow the screw-shank l when the same is withdrawn. When actuating the cutting-tool toward the pipe or rod, the flange abuts directly against the holder, as will be obvious.

I claim as new, and desire to secure by Letters Patent—

1. The cutting-tool d, consisting of a fixed steel cutter, pointed substantially as shown and described, in combination with the screw-shank l, stock A, and adjustable claw B, all constructed and operating as and for the purpose set forth.

2. The flange i and pin g, substantially as shown and described, or other equivalent device, when in combination with the holder G, stock A, and cutting-tool d, for the purpose set forth.

3. The slot n, substantially as shown and described, in combination with the cutting-tool d and stock A, all as set forth.
